FIG. 5.

FIG. 6.

INVENTOR

Joseph Simmons

BY
Edgar A. T. & Co.
ATTORNEYS.

UNITED STATES PATENT OFFICE.

JOSEPH SIMMONS, OF NEW YORK, N. Y.

TOOTH-BRUSH.

1,285,815.

Specification of Letters Patent.

Patented Nov. 26, 1918.

Application filed December 15, 1917. Serial No. 207,281.

To all whom it may concern:

Be it known that I, JOSEPH SIMMONS, a citizen of the United States, and residing at New York, in the county of New York and

5 State of New York, have invented certain new and useful Improvements in Tooth-Brushes, of which the following is a specification, such as will enable those skilled in the art to which it appertains to make and

10 use the same.

This invention relates to tooth brushes, and particularly to devices of this class which involve an independent brush member and a handle detachably connected therewith, and the invention described and claimed herein consists of the means employed for detachably connecting the handle with the brush member.

15 The invention is fully disclosed in the following specification, of which the accompanying drawing forms a part, in which the separate parts of my improvement are designated by suitable reference characters in each of the views, and in which:—

20 Fig. 1 is a side view of a tooth brush made according to my invention with part of the construction broken away;

Fig. 2 a back view showing the brush member in one position in full lines and indicating it in another position in dotted lines;

Fig. 3 a partial section on the line 3—3 of Fig. 2;

Fig. 4 a front view of the means employed for connecting the handle with the brush member;

Fig. 5 a view similar to Fig. 3 but showing a modification; and,

Fig. 6 an inside view of the construction shown in Fig. 5.

In the accompanying drawing, Figs. 1 to 4 inclusive, I have shown a tooth brush *a* comprising an independent brush member or body *b*, and a handle *c* with which the brush member or body *b* is pivotally connected so that it may rotate on the handle.

The brush body or member *b* is composed of a back *b*² and bristles *b*³ connected with the back in the usual or any desired manner, and the back *b*² is curved or arc-shaped in form longitudinally.

The back *b*² may be formed from any suitable material, preferably celluloid, bone, hard rubber or any other desired substance, and in the back surface thereof is formed a flat longitudinal groove *b*⁴ adapted to re-

ceive a plate spring *d* which fits therein, in other words, is countersunk or adapted to be countersunk in the back *b*².

Inwardly of the opposite ends of the groove *b*⁴ in the back *b*² are formed transverse recesses *b*⁵ and the plate spring *d* is shorter than the back of the brush and is provided at its ends with transverse beads or lock devices *d*² adapted to fit in the recesses *b*⁵ and which lock the plate spring to the back *b*², this connection being a detachable one and by reason of this construction the use of the brush in the mouth is facilitated, the ends of the back or body of the brush being made smooth and even, or practically with an unbroken surface.

The transverse beads or lock devices *d*² are preferably formed by rolling the ends of the spring *d* inwardly and downwardly as shown but these beads or lock devices may be formed in any desired manner, all that is necessary in this connection being that the spring with its beads or lock devices be shorter than the back or body of the brush and that the recesses *b*⁵ be inwardly of the ends of said back or body of the brush, and that said recesses be so formed that when the spring *d* is pressed into position in the back *b*², the parts *d*² of said spring will enter the recesses *b*⁵ and detachably engage the back *b*². This connection of the spring *d* with the back *b*² of the brush is such that the brush may be freely used at all times in the usual manner without disengaging it, or disconnecting it from the handle or the spring *d* which is connected with the handle, but the said spring *d* may be disengaged from the back of the brush at any time, when desired, by forcing a suitable implement under one end portion of said spring.

The pivotal connection of the handle with the plate spring *d* is shown in Figs. 1 to 4 inclusive, and in this operation a rivet or similar device *e* is employed, and the head *e*² of the rivet *e* is countersunk in the inner or front sides of the plate spring *d*, and said rivet is passed through the center countersunk portion of the spring *d* and through the end of the shank of the handle *c* as shown at *c*², and the outer end of said rivet is headed as shown at *e*³, but this pivotal connection of the plate spring *d* with the handle *c*, or the shank *c*³ of the handle may be made in any desired manner.

In Figs. 5 and 6, I have shown the handle,

or the shank thereof, rigidly connected with the plate spring *d* and in this construction the rivet *e*⁴, as shown, is made integral with the shank of the handle and the head *e*⁵ of said rivet is made angular in form and countersunk in the bottom of the plate spring *d*.

By pivotally connecting the brush with the handle, said spring may be used in the same manner as that described and claimed 10 in U. S. Letters Patent granted to me May 4, 1915, No. 1,137,916, or when the handle is rigidly connected with the spring *d* the brush is used in the same manner as other 15 devices of this class, or when the handle is formed integral with the back of the brush, or rigidly connected therewith in any way.

It will be understood that the longitudinal curvature of the back of the brush when the construction shown in Figs. 1 to 4 inclusive is employed, may be varied to a considerable extent, and the brush body or brush member may be made in a number of different forms in longitudinal section varying from a curvature similar to that shown 25 to a U-shaped or box-shaped form, and this is also true of the construction shown in Figs. 5 and 6.

With my improvement a new brush or brush body may be substituted for an old 30 one whenever desired, and the parts *b*² and *d* may be disconnected whenever necessary for cleaning or other purposes.

Having fully described my invention,

what I claim as new and desire to secure by Letters Patent, is:—

1. A tooth brush, comprising a brush member and a detachable handle member, the back of the brush member being curved and provided with a groove in its outer surface at the ends of which are transverse recesses and the handle member being provided with a curved spring attaching device rotatably connected therewith and adapted to fit said groove and provided at its ends with locking devices adapted to fit 40 in said recesses.

2. A tooth brush comprising a brush member and a detachable handle member, the back of the brush member being convex in longitudinal section and being provided 50 with a longitudinal groove in its outer surface and inwardly of the ends thereof with transverse recesses and the handle member being provided with a curved spring attaching device shorter than the back of the brush 55 and adapted to fit in said groove and provided at its ends with transverse locking devices adapted to fit in said recesses.

In testimony that I claim the foregoing as my invention I have signed my name in 60 presence of the subscribing witnesses this 13th day of December, 1917.

JOSEPH SIMMONS.
